UNITED STATES PATENT OFFICE.

ROBERT STEEL, OF PHILADELPHIA, PENNSYLVANIA, ASSIGNOR OF ONE-HALF TO VIRGIL W. WALTER, OF SAME PLACE.

FURNACE.

SPECIFICATION forming part of Letters Patent No. 373,030, dated November 8, 1887.

Application filed May 18, 1886. Serial No. 202,581. (No model.)

To all whom it may concern:

Be it known that I, ROBERT STEEL, a citizen of the United States, residing at Philadelphia, in the county of Philadelphia and 5 State of Pennsylvania, have invented certain new and useful Improvements in Furnaces, of which the following is a specification.

The invention consists in the combination, with a furnace for generating heat, inclosed 10 with an outer larger casing, and provided with a combustion-chamber, hot-air radiating and smoke-exit flues, of a pair of fans or blowers arranged, respectively, in the upper portions of said chambers, which rotate with a 15 vertical spindle which passes through the upper wall of the combustion-chamber, and a boiler located within said chamber above the fire-pot, containing water for generating steam that finds its exit through a pipe leading in 20 proximity to the blades of the fan in the combustion-chamber, whereby the current is caused to impinge upon said blades and rotate the fans. The fans may be rotated by currents of either steam or hot air, caused to impinge 25 upon the blades, or the fan in the hot-air chamber may be operated independently of the other, as will be more fully hereinafter described.

In the accompanying drawings, which make 30 a part of this specification, Figure 1 is a plan view of my improved furnace with the top *a* removed. Fig. 2 is a like view with the tops *a'* and fan *G* removed. Fig. 3 is a front elevation with the front halves of the walls of the 35 fire-pot *A* and chamber *B* removed. Fig. 4 is a top view of the boiler or steam-drum *J*.

Like letters of reference in all the figures indicate the same parts.

A is the fire-pot, having the customary 40 grate, *b*, for the reception of fuel, and ash-pit provided with the door *C*. The fire-pot is surrounded by the metallic casing *c*, forming a chamber, *B*, for the reception of radiated heat, and also a passage for the ascension of 45 currents of air through usual inlet-openings in the bottom of the furnace.

D is the smoke and gas exit flue. *E* are exit-flues for hot air. These parts are common to all furnaces, and a particular description 50 thereof is unnecessary.

G is a fan or blower arranged in the upper part of the chamber *B*, consisting of a series of wings or radiating blades centering upon the hub *d*, rigidly secured upon the spindle

H, which has its upper bearing in the cap- 55 plate *a* of the furnace, the lower bearing being arranged in any suitable device. Secured upon the lower end of said shaft, within the upper end of the drum above the fire-pot, is the fan *G'*, constructed in like manner to the 60 fan *G*, which in the present instance is for the purpose of imparting rotary motion to the fan *G* by means of a current of steam issuing from the exit-pipe *e* of the boiler *J*, acting upon the surfaces of the blades, causing rotary 65 movement to be imparted thereto.

The boiler *J* is situated within the fire-pot and supported by the walls thereof immediately above the mass of ignited fuel, receiving heat therefrom for the generation of steam 70 within it.

h is the inlet-pipe for the admission of water, which may be supplied by any known means.

The drawings illustrate a means for imparting 75 rotary motion to the fan *G*; but I do not confine myself to this method, as any known mechanical means, or a current of air or steam forced directly upon the surfaces of its blades, whereby it is caused to rotate and force 80 the current of air charged with radiated heat up and into the exit-flues *E*, may be employed, my invention consisting in the employment and combination, with a furnace for generating heat, of a fan or blower arranged as shown 85 and described, and rotated by any means to effect the desired purpose.

I claim as my invention and desire to secure by Letters Patent—

The combination of the combustion-chamber, 90 the outer casing forming the hot-air chamber, the shaft for supporting the fans passing through the upper wall of the combustion-chamber, the fans mounted on said shaft, located, respectively, in the upper parts of said 95 combustion and hot-air chambers, and the boiler having a pipe whose end is in proximity to the blades of the fan in the combustion-chamber, whereby the current of steam emanating from the boiler is caused to impinge 100 upon said blades and cause rotation of the fans, substantially in the manner herein shown and described.

ROBERT STEEL.
